UNITED STATES PATENT OFFICE.

DOMINICK A. McDONALD, OF ROCKLAND, MAINE, ASSIGNOR OF ONE-HALF
TO WILLIAM P. HURLEY AND JOHN E. HANLEY, OF SAME PLACE.

CRIMPING-MACHINE.

SPECIFICATION forming part of Letters Patent No. 269,693, dated December 26, 1882.

Application filed August 24, 1882. (No model.)

To all whom it may concern:

Be it known that I, DOMINICK A. McDONALD, a subject of the Dominion of Canada, having made oath of my intention to become 5 a citizen of the United States, and having resided at Rockland, in the county of Knox and State of Maine, during four years last past, and being now a resident of said Rockland, have invented a new and useful Crimping- 10 Machine, of which the following is a specification.

My invention relates to improvements in crimping-machines where the crimping and stretching are done at once; and the objects 15 of my improvements are, first, to lessen the number of times of handling the leather or substance to be crimped and to stretch more perfectly the article crimped. I attain these objects by the mechanism illustrated in the 20 accompanying drawings, in which—

Figure 1 is a side view of the machine or block as it appears before the leather is attached; Fig. 2, an end view of the same. Fig. 3 is a cross-section of the block; Fig. 4, the clamp; 25 Fig. 5, a perspective view of the block with the leaves raised; Fig. 6, an end view with leather attached; Fig. 7, an end view with leaves closed and clamp on.

Similar letters refer to similar parts throughout the several views.

In Fig. 1, *a* is the frame-work, shaped on top to suit the article for which a cover is to be crimped, with the movable side leaves, *b b*,

hinged to the main block at their tops, so as to leave a smooth, unbroken surface when the 35 leaves are closed. *c c* are the hinges. *e* is the clamp which secures the leaves in position when the leather is being stretched, and *d d d* are the spurs, which project from the inner side of the leaves in a depression along their edges 40 to detain the leather under tension.

In practice, the body-piece *a* being first shaped to correspond to the form desired, whether it be a front for a boot or shoe or a cover for a saddle-tree, the leaves will then be 45 given a contour corresponding to the form of the leather, which experience has shown is suitable for the desired cover, the leaves being spread out as in Fig. 5, and the leather drawn over the form as in Fig. 6. Then by pressure 50 on the leaves they are brought into position with the hands as in Fig. 7 and the clamp *e* sprung into position.

What I therefore claim as my invention, and desire to secure by Letters Patent, is— 55

1. The combination, with the body *a*, of the leaves *b*, hinged thereto, and provided with the spur-hooks *d*, as and for the purpose specified.

2. The combination, with the body *a* and the leaves *b*, provided with the spur-hooks *d*, of the 60 spring-clamp *e*, adapted to embrace the leaves *b* when folded, as and for the purpose specified.

DOMINICK A. McDONALD.
